UNITED STATES PATENT OFFICE.

GEORGE BRENNER, OF CLEVELAND, OHIO, ASSIGNOR OF ONE-HALF TO
CHARLES BRENNER, SR., OF SAME PLACE.

DRUM FOR TURNING-LATHES.

SPECIFICATION forming part of Letters Patent No. 357,453, dated February 8, 1887.

Application filed August 13, 1886. Serial No. 210,817. (No model.)

To all whom it may concern:

Be it known that I, GEORGE BRENNER, a citizen of the United States, residing at Cleveland, in the county of Cuyahoga and State of Ohio, have invented certain new and useful Improvements in Drums for Turning-Lathes; and I do hereby declare that the following is a full, clear, and exact description of the invention, which will enable others skilled in the art to which it appertains to make and use the same.

My invention relates to a drum or head for holding balusters, spindles, table-legs, moldings, &c., for square turning, the object of the invention being to provide a device of this character which shall be simple in its construction, effective in its operation, and in which the articles to be turned may be readily placed without removing the heads of the drum.

With the above and other objects in view, the invention consists in the improved construction and combinations of parts herein-after fully described, and pointed out in the claims.

In the drawings, Figure 1 is a perspective view of a turning drum or head embodying my invention. Fig. 2 is a longitudinal vertical section. Fig. 3 is a vertical transverse section, and Figs. 4 and 5 are detail views of parts detached.

Corresponding parts in the several figures are denoted by the same letters of reference.

Referring to the drawings, A represents a threaded rod, at one end of which is provided an annular shoulder, a.

B represents a head, which is fitted on the threaded rod A, and which bears against the inner side of the annular shoulder a, and secured thereto in any suitable manner. The head B is provided with an inwardly-extending circumferential flange, b, and secured in recesses c, adjacent to the center of the head, and on the inner side thereof are flat springs d, the outer ends of which are free. The threaded rod A is provided with a longitudinal groove or channel, C, and fitting on said threaded rod is a plate, D, which is received within the head B. This plate D has a central opening to receive the threaded rod A, and

surrounding said opening is a collar, d', preferably rigid with the plate.

Projecting into the central opening of the plate D is a feather or spline, e, which is adapted to engage the groove or channel C on the threaded rod A, thus preventing said plate from turning, it being held in place upon the rod against longitudinal movement by means of a nut, f, which engages the threaded rod A, and which, when screwed up tight, bears against the collar d'.

Upon the outer side of the plate D are secured, near the center thereof, flat springs similar to those already described on the head, and when said plate is in position its springs are located between those of the head. The nut f is left loose enough to allow a slight movement of the head, which, however, is held in engagement with the nut by the flat springs. Upon the other end of the threaded rod is provided a head and plate similar in construction to those already described; but in this case they are removable, being held in place upon the rod by a nut, g.

In operation the squares, strips, or pieces of material to be turned are placed with their ends resting on the inner faces of the heads, the flat springs being compressed and the plates forced against the heads, thus confining the strips. The inward movement of the strips is prevented by circular ledges located a short distance from the peripheral edges of the plates, and against which the inner edges or faces of the strips being operated upon bear.

It will be seen that by providing the spring-held plates strips of different lengths may be placed in the drum for turning, and that it is unnecessary to remove the heads or plates for their insertion in the drum. When the strips have been turned on one side they are removed, and their other sides turned one after the other.

Having thus described my invention, what I claim as new, and desire to secure by Letters Patent, is—

1. The combination, with a rod, of heads arranged at the ends thereof and spring-actuated plates located on said rod, the springs being disposed between the relative heads and plates, as set forth.

2. The combination, with a rod, of heads located at the ends thereof and spring-actuated plates located on the rod inside the heads, the plate and head at one end of the rod being re-
5 movable, as set forth.

3. The combination, with a rod, of heads having inwardly-extending flanges at their periphery and plates located on the rod and disposed within the said flanged periphery, said 10 plates having ledges between which and the flanged periphery the pieces to be turned are seated, as set forth.

4. The combination, with a rod, of heads hav-

ing flat springs secured to their inner faces and plates located on the rod and adjustable 15 with relation to the heads, said plates having flat springs secured to their outer faces and acting against the inner face of the heads, as set forth.

In testimony whereof I affix my signature in 20 presence of two witnesses.

GEORGE BRENNER.
